BENJAMIN JONASSEN
ATTORNEY

UNITED STATES PATENT OFFICE

JACOB GOTTLIEB, OF NEW YORK, N. Y., ASSIGNOR TO GOTTLIEB BROS. AND LACHMAN, INC., OF NEW YORK, N. Y., A CORPORATION OF NEW YORK

INFANT'S BATHTUB

Application filed May 6, 1929. Serial No. 360,733.

This invention relates to infant's bath tubs, and particularly to appliances for the same that are demountably placed therein for maintaining the baby in elevated or tilted 5 position during the bathing.

The principal object of the invention is to provide a simplified, inexpensive, conveniently and economically manufaturable, strong, durable, and improved bath tub appliance 10 for the above mentioned purpose, which may be rapidly, conveniently, and efficiently mounted upon and demounted from the infant's bath tub, and rapidly, conveniently, and efficiently tilted to any required position.

15 Other objects and advantages will herein-after appear.

In the accompanying drawings:—

Fig. 1 is a perspective view of the infant's bath tub and of the appliance constituting 20 this invention.

Fig. 2 is a fragmentary view showing an end elevation of a portion of the appliance shown in Fig. 1.

Fig. 3 is a cross sectional end elevation, 25 in an enlarged scale, of the locking means for adjustment of the suspension straps forming part of the appliance shown in Fig. 1.

Figs. 4, 5, 6, and 7 shows modifications of the invention.

30 The bath tub appliance 1 proper comprises a U-shaped frame 2, preferably of metal rod, over which is stretched a sheet 3 of canvass or other suitable material, which is secured thereto by sewing or in any other desirable

35 manner. The ends 4 of frame 2 are bent upwardly, thereby forming a pair of suspenders 5 for that end or side of the sheet 3 and frame 2, and the terminals 6 of said suspenders are bent laterally so as to form pro-

40 jections which enter holes 7 provided in the side walls 8 of the infant's tub 9, in which manner the sheet 3 and frame 2 are supported and hingedly joined at side 10 to the tub 9. To the opposite side 11 of the frame 2 is se-

45 cured a pair of straps 12, made of canvass or any other suitable material, each of which is provided with a series of elongated holes 13 adapted to co-operate with a locking device 14 secured to the exterior of the tub 9. The

50 device 14 comprises a stationary member 15

which is secured to the tub-wall 8 and an elongated member 16 pivoted to member 15, whereby when the member 16 is in the vertical position shown in Fig. 3 the entire device may be passed through any one of the openings 55 13 of straps 12 and the member 16 may be then turned horizontally to the position shown in Fig. 3 to join the strap to the device and lock it in this manner. When it is desired to utilize the appliance 1 it may be 60 readily mounted in the tub 9 by springing the suspender bar portions 5 toward each other and releasing them to project their terminals 6 into the holes 7, and then joining the straps 12 to the tub-walls 8 by interlocking the holes 65 13 with the devices 14. Slipping the last or outermost holes 13 over the devices 14 will retain the appliance and sheet 3 in the horizontal position shown in Fig. 1, while slipping either of the remaining holes 13 over 70 said devices will tilt the sheet to the extent required.

According to the modification shown in Figs. 4, 6, the terminal 17 of each strap 12 has joined thereto a spring cleat 18 which is 75 adapted to embrace and grip the top rail 19 of the tub-wall 8 to thereby retain the straps 12 and appliance 1 in position. Shifting of the cleat 18 laterally along the rail 19 will tilt the side 11 of sheet 3 and frame 2 to any 80 degree required. Preferably a series of projections or heads 20 may be secured to the inner side of rail 19, between either pair of which the cleat may be placed when adjusting the position of the straps 12, and these 85 heads will prevent accidental lateral shifting or displacement of the cleats after such adjustment.

In the modification shown in Fig. 5 the cleat 21 is made rigid and fits over the rail 19, and a thumb screw 22 threads therethrough and against the rail in the manner shown to thereby secure the cleat to any desired position along the rail 19.

According to the modification shown in Fig. 7 the ends 4^a of the frame 2 are shaped to 95 form eyes 23, through which passes a horizontal rod 24 the ends of which are bent upwardly to form a pair of suspenders 5^a with laterally bent terminals 6^a which may be 100

sprung into the holes 7 of the tub 9. The suspenders 5^a therefore operate in the same manner as the above described suspenders 5, and the advantage of this modification is that when demounting this appliance from the tub it may be completely collapsed, as the eyes 23 and rod 24 act as a hinge to thus bend over the suspenders 5^a to fold alongside the frame 2.

10 It will be evident that the appliance 1 is very readily demounted by merely springing the projections 6 or 6^a out of the holes 7 and releasing the straps 12 from the upper tub-rail 19.

15 Variations may be resorted to within the scope of the invention, and portions of the improvements may be used without others.

Having thus described my invention, I claim:—

20 1. An infant's bath tub having a sheet for supporting the body, a frame for supporting said sheet comprising a U-shaped rod the ends of which project upwardly to constitute suspenders for the frame, the terminals of said ends being pivoted to the bath tub, and means for suspending the opposite side of said frame.

25 2. An infant's bath tub having a sheet for supporting the body, a frame for supporting said sheet comprising a U-shaped rod the ends of which project upwardly to constitute suspenders for the frame, the terminals of said ends being pivoted to the bath tub, a pair of straps for suspending the opposite side of said frame being joined to said frame, the bath tub having a device for each of said straps for locking the latter thereto, and each of said straps having a series of cooperating locking devices for locking the strap at a plurality of points for adjusting the elevation of said side of the frame.

30 3. An infant's bath tub having a sheet for supporting the body, a frame for supporting said sheet comprising a U-shaped rod the ends of which project upwardly to constitute suspenders for the frame, the terminals of said ends being pivoted to the bath tub and being removable from the bath tub, a pair of straps for suspending the opposite side of said frame being joined to said frame, the bath tub having a device for each of said straps for locking the latter thereto, and each of said straps having a series of cooperating locking devices for locking the strap at a plurality of points for adjusting the elevation of said side of the frame.

35 4. An infant's bath tub having a sheet for supporting the body, a frame for said sheet, rigid suspenders for one side of said frame having their terminals pivoted to the bath tub, and means for suspending the opposite side of said frame.

40 5. An infant's bath tub having a sheet for supporting the body, a frame for said sheet, rigid suspenders for one side of said frame

having their terminals pivoted to the bath tub, said suspenders being also pivoted to said frame, and means for suspending the opposite side of said frame.

45 6. An infant's bath tub having a sheet for supporting the body, a frame for said sheet, suspenders for one side of said frame joined to said sheet and to the bath tub, a pair of straps for suspending the opposite side of said frame being joined to said frame, the bath tub having a device for each of said straps for locking the latter thereto, and each of said straps having a series of cooperating, locking devices for locking the strap at a plurality of points for adjusting the elevation of said side of the frame.

50 7. An infant's bath tub having a sheet for supporting the body, a frame for said sheet, suspenders for one side of said frame joined to said sheet and to the bath tub, a pair of straps for suspending the opposite side of said frame being joined to the frame, each of said straps having a spring clip for gripping the bath tub wall at a plurality of places for adjusting the elevation of the latter side of the frame, and the bath tub having a plurality of projections for preventing lateral shifting of said clip after adjustment.

55 Signed at New York, in the county of New York, and State of New York, this 4th day of May, A. D. 1929.

JACOB GOTTLIEB.
